UNITED STATES PATENT OFFICE.

WILLIAM M. TAYLOR, OF INDIANAPOLIS, INDIANA, ASSIGNOR OF ONE-HALF, BY MESNE ASSIGNMENTS, TO ULYSSES GRANT SMITH, OF INDIANAPOLIS, INDIANA.

MOLDBOARD BALANCE.

Application filed May 13, 1926. Serial No. 108,812.

This invention relates particularly to the counter-balancing of the mold board of road making machines to assist in lifting and holding the mold board off of the ground 5 when it is desired to turn the machine at the end of its travel or to haul the machine from place to place when it is not at work scraping.

A further object is to utilize the resiliency 10 of a spiral spring in supporting a mold board which has lateral and rotary and also vertical adjustment, and to provide means at all of said adjustments for equalizing the variable tension of the spring which increases 15 as the spring is wound up.

I accomplish the above, and other minor objects which will hereinafter appear, by the means illustrated in the accompanying drawing, in which—

20 Fig. 1, is a view in side elevation, of enough of the mechanism of a road machine to make the application of my invention which is shown therein, intelligible,

Fig. 2, is a vertical cross section on the 25 line 2—2 of Fig. 1, and

Fig. 3, is a detail, in side elevation, of a spring with chain-winding cone at one end, and worm and wheel mechanism at the other end for winding the spring.

30 Like characters of reference indicate like parts in the several views of the drawing.

The body frame 1 is mounted on front wheels 2 and rear wheels 3, and supported below the body frame between wheels 2 and 35 3, is a draft bar 4, from which a mold board 6 is suspended, and is rotatably adjustable around a vertical pivot 7. The draft bar 4 has a wide rear end 5, and tapers toward its front hinge end 8. Attached to the rear end 40 of the draft bar 4 is a yoke (a) having a tube in which a bar (b) telescopes to allow the bar to shorten and lengthen with the swing of the yoke. The bar (b) is connected by a link (c) with a member (d) which has sliding adjustment on a T-bar (e) fixed to the rear axle of the machine. The yoke is adjusted laterally by sliding the member (d) on bar (e) in the proper direction.

The position of the mold board 6, relative 50 to the ground, is thus controlled by the position of the draft bar, whereby, by raising and lowering the draft-bar the mold board will be correspondingly moved.

It may also be moved longitudinally by 55 swinging the rear end of the draw-bar 4

about its front end 8 and correcting the angle by rotating it about pivot 7.

Supported upon and attached to the draft-bar is a horizontal channel bar 9, which extends a suitable distance on each side laterally of the draft-bar, as shown in Fig. 2, to afford better control of the draft-bar from the body-frame of the machine.

Mounted upon the body-frame 1, substantially over the bar 9, are two, parallel bars 65 10 and 10', which provide supports for vertical frames 11, 11, having slide-ways there-in for vertical rack-bars 12, 12, and journal bearings for shafts 13, 13, upon which are the respective spur-gear wheels 14, 14, which 70 engage with the teeth on adjacent rack-bars 12.

The lower ends of the rack-bars 12, 12, are each connected by crank arms 15, 15, with respective ends of the bar 9 on the draft-bar, 75 and to allow for the necessary adjustment of the mold-board laterally of the machine as a whole the ends of the crank arms are connected with the cooperative parts by universal joints, here shown as by ball and socket 80 joint 16, 16, and double hinge joints 17, 17.

The shafts 13, 13, are each extended to the rear of the body frame, and terminate with worm wheels 18, which are engaged by respective worms 19 on shafts 20, and on the 85 shafts 20 are hand wheels 21.

By manipulation of the hand wheels 21 the intervening mechanism will raise or lower the mold board, and any given adjustment will be held by the worm and wheel portions thereof. The approximate weight of the mold board is 2000 pounds, and it is the main purpose of my invention so to counterbalance the weight that approximately half of the weight will be taken off of the shaft 20 90 and associated gears, and less exertion by the operator on the hand wheels 21 will be required to raise the respective ends of the mold board. It is also a feature of my invention to counter-balance the weight of the mold board at any of its rotary and laterally 95 adjusted positions.

I will now describe the mechanism by which the weight of the mold board is counterbalanced. Secured to the under side of the body-frame 1 are two transverse bars 22, 22, which assists the bars 10 and 10' in supporting shafts 23, 23, on one end of each of which a worm wheel 24 is rotatably mounted, and upon which shafts near their 110

other ends, are integral castings each comprising a cone 25 having a flange 27 at its inner end. Each shaft 23 passes through a spacing pipe 28 which keeps the flanged end 5 27 at a uniform distance from the wheel 24. A spiral spring 29, is wrapped around each pipe 28. One end of each spring passes through a hole in the adjacent wheel 24 and the other end of the spring passes in like 10 manner through a hole in adjacent flange 27.

A worm 30 operates to rotate the worm wheel 24 when the worm is rotated, and at all other times to hold the worm wheel from rotating. The ends of shafts 31, 31, on 15 which the respective worms 30 are mounted, are suitably squared to receive a wrench for manual rotation of the worm.

Chains 32, 32, are attached at one end of each to corresponding eyes 33, 33, pivoted 20 to bar 22, and are extended down and under respective pulleys 34, 34, mounted on bar 9, thence up and over respective pulleys 35, 35, carried by the frame 1 on suitable frame members, not shown, and thence to the inner 25 end of the spiral groove in the adjacent cone 25 and is fastened there to the small end of the cone in position to be wrapped upon the cone by the continued wrapping of its spring 29. The grip of the chain in the cone is 30 made positive by indents 36, formed in the grooves to receive the links of the chains; and the varying diameters of the cones equalize the tension of the springs by changing the leverage as the springs are more 35 tightly wound.

It will be noted that the spring-balance mechanism is in duplicate, one for each side of the machine or mold board end, for the reason that an independent adjustment for 40 each end of the mold board is often required.

In the operation of my device it is generally desirable to use stiff enough springs to lift half of the weight of the mold board, leaving approximately the other half of the 45 weight to be raised by the mechanism manually operated through hand wheels 21. The thousand pounds to be balanced by my invention is equally divided between the above described duplicate mechanisms for the two 50 ends of the mold board. Accordingly, each of the two springs 26 is manually tightened by rotating its worm 30, until the spring will raise 500 pounds. If this mold board be in raised position when the spring is wound 55 the lowering of the mold board will wind the spring tighter, thereby increasing its tension, but this increase is compensated for by winding the chain on the larger diameters of the cone, thereby increasing the leverage. 60 The opposite occurs should the mold board be in lowered position when the springs are wound up. The above described mechanism is operative at any position of the mold board within its range of adjustment vertically, 65 laterally and rotatively.

It is sometimes desirable to detach the mold board, as for sharpening, repairs and the like, and the tension of the springs is retained by locking the cones by inserting a pin 40 through a hole in the frame member 70 41, into a registering hole in the end disk 42 of the cone.

I claim:

1. In a road making machine, a mold-board adapted to be moved up and down, 75 in combination with means for balancing the mold-board at any position within its range of movement comprising a chain connected to the mold-board, and a cone on which the chain is wound, the axis of the cone extending longitudinally of the machine.

2. In a road making machine, a mold-board adapted to be moved, in combination with means for balancing the mold-board at any position within its range of movement comprising a chain connected to the mold-board, and a cone having a spiral groove in which groove the chain is wound, the axis of the cone extending longitudinally 90 of the machine.

3. In a road making machine, a mold-board adapted to be moved up and down, laterally of the machine and rotatably about a vertical axis, in combination with means for balancing the mold-board at any position within said range of movement comprising a chain connected to the mold-board, a cone with a spiral groove on which the chain is wound and a spring wrapped around the extended axis of the cone and attached to the 95 cone to balance the action of gravity on the mold-board.

4. In a road making machine, a mold-board adapted to be moved up and down, laterally of the machine and rotatably about a vertical axis, in combination with means for balancing the mold-board at any position within said range of movement comprising a chain connected to the mold-board, a cone with a spiral groove on which the chain is wound and a spring wrapped around the extended axis of the cone and attached to the cone to balance the action of gravity on the mold-board, and means for varying the tension of the spring.

5. In a road making machine, a mold-board adapted to be moved up and down, laterally of the machine and rotatably about a vertical axis, in combination with means for balancing the mold-board at any position within said range of movement comprising a chain connected to the mold-board, a cone with a spiral groove on which the chain is wound and a spring wrapped around the extended axis of the cone and attached to the cone to balance the action of gravity on the mold-board, and worm and wheel means for securing and retaining the required tension of the spring.

6. In a road making machine, a mold-board adapted to move up and down, laterally of the 130

- machine and rotatably about a vertical axis in combination with means for raising and lowering the mold-board and means for balancing the mold-board at any position within its range of movement comprising a chain connected to the mold-board, a cone with a spiral groove on which the chain is wound, the axis of the cone extending longitudinally of the machine, a shaft on which the cone is mounted having an extended portion, a spring wrapped around the extended portion of the shaft and attached to the cone at one end and to a fixed support relative to the cone at the other.
- 15 7. In a road making machine, a mold-board adapted to move up and down, laterally of the machine and rotatably about a vertical axis in combination with means for raising and lowering the mold-board and means for balancing the mold-board at any position within its range of movement comprising a chain connected to the mold-board, a cone with a spiral groove on which the chain is wound, the axis of the cone extending longitudinally of the machine, a shaft on which the cone is mounted having an extended portion, a spring wrapped around the extended portion of the shaft and attached to the cone at one end and to a fixed support relative to the cone at the other and means for varying the tension of the spring.
8. In a road making machine, a draw-bar, a mold-board pivotally supported at its middle from the draw-bar and rotatable on said pivot said draw-bar extending back of the pivot approximately to the circle described by the ends of the mold-board, in the rotary adjustment of the mold-board and means for adjusting the mold-board vertically, in combination with means for balancing the mold-board at any position within its range of

movement comprising a chain connected to the end of the draw-bar, a cone-wheel on which the chain is wound and a spring to resist the rotation of the cone-wheel by the weight of the mold-board.

9. In a road making machine, a machine body, pulleys supported by the machine body and a mold-board adjustable in position in combination with means for balancing the mold-board at any position within its range of movement comprising a chain connected to the mold-board, a cone on which the chain is wound and a spring resisting the movement of the cone by the weight of the mold-board exerted through the chain, said chain passing around the pulleys on the machine-body.

10. In a road making machine, a mold-board movable up and down, laterally of the machine and rotatively, in combination with means for raising and lowering the mold-board and means for balancing it at any position comprising a chain connected to the mold-board, a cone on which the chain is wound, and a torsion spring resisting the movement of the cone by the weight of the mold-board exerted through the chain.

11. In a road making machine, a mold-board movable up and down, laterally of the machine and rotatively, in combination with means for raising and lowering the mold-board and means for balancing it at any position comprising a chain connected to the mold-board, a cone on which the chain is wound, and a torsion spring resisting the movement of the cone by the weight of the mold-board exerted through the chain and means for changing the tension of the torsion spring.

In testimony whereof I affix my signature.
WILLIAM M. TAYLOR.
